UNITED STATES PATENT OFFICE.

JOHN LEWIS MANN, OF SMITHTON, WEST VIRGINIA, ASSIGNOR TO THE CASTLE BROOK CARBON BLACK COMPANY, OF WILLIAMSPORT, PENNSYLVANIA.

LAMPBLACK APPARATUS.

SPECIFICATION forming part of Letters Patent No. 706,429, dated August 5, 1902.

Application filed February 8, 1902. Serial No. 92,445. (No model.)

To all whom it may concern:

Be it known that I, JOHN LEWIS MANN, a citizen of the United States, residing at Smithton, in the county of Doddridge and State 5 of West Virginia, have invented a new and useful Carbon-Black-Making Apparatus, of which the following is a specification.

The object of the present invention is to provide new and useful improvements in the 10 form of carbon - black - making apparatus shown in the copending applications of John H. Mann, one of which was filed April 26, 1901, Serial No. 57,567, and the other June 27, 1901, Serial No. 66,300.

15 One of the specific features of the improvements consists in the provision of a new form of carbon-collecting wheel which is arranged for collecting carbon upon its opposite sides, as well as upon the outer periphery thereof, 20 whereby a much greater collecting-surface is provided.

Another object is to provide for scraping the opposite sides as well as the outer periphery of the collecting-wheels, and thereby 25 to secure such carbon-black as would be otherwise lost.

Another object is to provide an improved 30 type of burner wherein the burner-tips may be readily and conveniently adjusted with respect to the carbon-collecting wheels, so as to secure proper carbon-producing effect.

It is furthermore designed to provide for 35 directing the flames from the burners to the collecting-wheels in such a manner as to secure the maximum carbon-producing effect and at the same time to secure the finest quality of black and also to have this means adjustable, so as to overcome the deleterious effects of changes in the atmosphere surrounding the apparatus.

40 With these and other objects in view the present invention consists in the combination and arrangement of parts, as will be herein-after more fully described, shown in accompanying drawings, and particularly pointed out in the appended claims, it being understood that changes in the form, proportion, size, and minor details may be made within the scope of the claims without departing

from the spirit or sacrificing any of the advantages of the invention.

In the drawings, Figure 1 is a central longitudinal sectional view of a carbon-black-making apparatus embodying the improvements of the present invention. Fig. 2 is a 55 cross-sectional view thereof. Fig. 3 is an enlarged detail cross-sectional view of one of the burners and the adjacent carbon-collecting wheel. Fig. 4 is an enlarged detail sectional view taken through a pair of adjacent 60 collecting-wheels. Fig. 5 is a detail longitudinal sectional view of one of the burner-tips. Fig. 6 is a detail plan view of one of the mantle-supporting frames.

Like characters of reference designate corresponding parts in all the figures of the drawings.

Referring to the drawings, 1 designates the casing of the apparatus, which is constructed of any suitable material, preferably sheet 70 metal. Within the lower portion of the casing there is provided a longitudinal receptacle 2, which is substantially V-shaped in cross-section and is designed to receive the carbon-black as it falls from the generating apparatus located above. At one end of the bottom of the hopper there is provided a discharge-chute 3, and extending throughout the bottom of the hopper is a worm or spiral conveyor 4, which is adapted to feed the carbon-black to the discharge-chute 3 for convenience in obtaining the product of the apparatus. This conveyor is driven, by means of the bevelled gears 5 and 6, from any suitable source of power. (Not shown.)

85 Located above the receptacle or hopper 2 and extending longitudinally of the apparatus is a pair of gas-service pipes 7, each of which is provided with a plurality of burners 8, one of which has been illustrated in detail in Fig. 3 of the drawings. Each burner consists of a tubular externally-screw-threaded stem portion 9, fitted into a corresponding screw-threaded opening in the top of the adjacent pipe 7 and having a head or body portion provided with a plurality of upstanding internally-screw-threaded nipples 10 and 11, preferably three in number, of which the

outer nipples 10 are of the same length, and the intermediate nipple 11 is somewhat shorter than the outer nipples. Into each of these nipples there is fitted an externally-screw-threaded burner-tip 12, whereby it will be understood that these tips are individually adjustable in a vertical direction. As best illustrated in Fig. 5, it will be seen that the upper end of each tip is provided with a sharply-tapered head 13, which is solid and provided with a central longitudinal comparatively small perforation or orifice 14, through which the gas is designed to escape in the form of a flame, while the greater portion of the stem or body of the tip is provided with an enlarged chamber 15, whereby the tip is in the form of a tube having a solid tapered head provided with a small longitudinal orifice or perforation.

In order that the flames from the burner-tips may be confined and prevented from spreading to any appreciable degree, there has been provided a flame-confining device in the nature of a foraminous elliptical-shaped band or mantle 16, which surrounds the burner-tips and is carried by means of a metallic frame 17, which is rabbeted externally, so as to provide a seat for the lower edge of the mantle. A pair of cross-bars 18 extend across the open elliptical frame and are provided at their centers with corresponding openings or eyes 19, which are spaced so as to loosely embrace the respective outer burner-tips in order that the frame and the mantle may be adjustably elevated thereon. To support the frame at any position upon the burner-tips, the outer tips are externally screw-threaded for their entire lengths, and upon each tip there is provided a pair of nuts 20, which embrace the respective cross-bars 18, so that by adjusting these nuts upon the tips the frame and the mantle may be raised or lowered in accordance with the conditions of the surrounding atmosphere. It will here be noted that while it is not necessary to have the central tip externally screw-threaded for its entire length, as the frame is supported upon the outer tip only, it will not affect the device in any manner whatever to have the central tip screw-threaded.

Above each gas-service pipe is a rotatable shaft 21, which is driven by a pair of bevel-gears 22 and 23, operated from the same source of power as are the gears 5 and 6. Upon each of these shafts is mounted a plurality of carbon-collecting wheels 24, one for each burner. As best indicated in Fig. 4 of the drawings, it will be seen that each wheel is hollow and comprises a hub 25, a flat disk-like end or head 26, integral with the hub, and a cylindrical rim 27, integral with the head 26 and projected in the direction of the hub, the latter having its outer end portion 28 extended beyond the open side of the wheel, so as to form a spacing device against which the next adjacent wheel is adapted to

bear, whereby all of the wheels are spaced at regular intervals. The wheel is secured to the shaft 21 by means of a fastening 29, passed through the projected hub portion and the shaft and having its opposite ends upset. Hence in addition to forming a spacing device the projected hub portion also facilitates the securing of the wheel to the shaft. The open side of the wheel is provided with a rabbeted marginal edge 30 and is closed by means of a flat disk or plate 31, having a central circular opening 32 to snugly receive the projected hub portion and also having its outer marginal edge snugly seated in the rabbeted portion 30 and secured by means of screw-fastenings 33, set through the plate and into integral ribs 34, formed upon the inner side of the rim of the wheel. It will of course be understood that the plate 31 is flush with the adjacent edge of the wheel and the fastenings 33 are flush with the outer face of the plate in order that this side of the wheel may be entirely free from projections, and thereby capable of being effectually scraped, as will be hereinafter explained.

As indicated in Fig. 2 of the drawings, it will be observed that the tops of the series of carbon-collecting wheels rotate outwardly in opposite directions, as indicated by the arrows, and in order that the carbon collected thereon may be scraped therefrom, so as to drop downwardly and be collected in the hopper or receptacle 2, there is provided a plurality of scrapers, one for each wheel, each comprising a stem or shank 35, provided at its lower end with a chisel scraping-blade 36, which rests against the inner portion of the external peripheral edge of the adjacent wheel. The upper end of the stem or shank is provided with a hook 37, which is loosely and detachably engaged through a perforation in a supporting-bar 38, disposed longitudinally above the adjacent series of wheels, whereby the lower free end of the scraper is capable of a swinging movement toward and away from the collecting-wheel. In order that the scraper may be normally held in engagement with the wheel, it is provided with a suitable weight 39.

As heretofore described, the opposite heads or sides of the collecting-wheels are solid and flat in order that such carbon as may escape the peripheries of the wheels may be collected upon the opposite heads thereof, and in order that the carbon thus deposited upon the heads of the wheels may be removed therefrom there is provided a plurality of scrapers, each of which consists of a metal rod 40, which is disposed transversely of the apparatus and lies in the space between adjacent wheels and immediately above the shafts 21, the opposite ends of the rods being supported in notches or seats 42, formed in supporting-bars 43, carried by the opposite sides of the casing. As plainly indicated in Figs. 1 and 4, it will be understood that these rods lie in

close proximity to the heads of the wheels, but out of contact therewith, so as to leave clear spaces between the scrapers and the adjacent heads of the wheels to permit of the 5 downward passage through said spaces of such loose carbon as may fall from the upper portion of the casing, and thereby to prevent choking of the wheels and the scrapers. By the disposition of the head flush with the opposite edges of the rim of the wheels the collecting-surface thereof is materially increased and the output of the apparatus is proportionately increased.

Above the space between the sets of carbon-collecting wheels is a perforate or foraminous rotatable carbon-collecting cylinder 44, which is adapted to collect such fine carbon as may be loosened by the scrapers and is carried upwardly by the draft through the 15 casing. Below this cylinder is mounted a rock-bar 45, which is provided with a plurality of brushes 46, lying in frictional engagement with the periphery of the cylinder to scrape therefrom the carbon which may collect thereon. One end of this rock-bar is projected through the end of the casing and provided with a weighted arm 47, which is disposed to normally hold the brushes in frictional engagement with the cylinder. Lying 20 between the cylinder and the scrapers 35 and disposed longitudinally at opposite sides of the brush 46 is a pair of downwardly-converged plates 48, which form a chute to collect the carbon scraped from the cylinder 25 and to direct the same downwardly through the space between the opposite sets of collecting-wheels. The foraminous cylinder is rotated by means of bevel-gears 49 and 50, which are in operative relation to the main 30 driving means, as explained for the other gears. The top or roof portion 51 of the casing is peaked and open longitudinally throughout its highest point, as indicated at 52, and from the edges of this opening depend the opposite inwardly-inclined screens 53, which are designed to prevent the escape of such minute particles of carbon as float upwardly from the rotatable cylinder. Over the top of the opening 52 there is a suitable 35 hood 54, which is spaced slightly above the top of the casing, so as to provide comparatively narrow marginal openings 55 between the outer edge of the hood and the top of the casing to permit the heated air to escape, and 40 thereby give the desired draft to the burners.

In the operation of the device the central tips of the burners are adjusted so as to lie at a predetermined distance from the peripheries of the collecting-wheels and then the 45 outer tips are adjusted so as to lie somewhat nearer the wheels, for the reason that the draft caused by the latter causes the outer flames to flicker and to be blown laterally, and therefore it is necessary to bring the outer flames nearer the wheels in order to obtain the maximum carbon-producing effect thereon. The flame-confining device or mantle 16 is then

adjusted upon the burner-tips, so as to properly confine the flames, and thereby prevent the latter from being blown laterally to any appreciable extent by the draft caused by the rotation of the collecting-wheels. It will here be noted that the flame-confining means is perforated and also open at the top and bottom in order that the proper amount of air 75 may be supplied to the burners, and therefore it will be understood that the purpose of the band or mantle is to confine the flames and insure their direct impact with the peripheries of the collecting-wheels in contradistinction 80 to the somewhat similar devices which have been used to produce an imperfect combustion for the purpose of causing the burners to smoke. It will here be noted that the burners and the mantle or flame-confining device 85 are independently adjustable, whereby after the burner-tips have once been adjusted the mantle may be adjusted vertically, according to the conditions of the atmosphere surrounding the machine, without interfering with the 90 previous adjustment of the burner-tips. It is also advantageous to have a comparatively small opening 14 in the burner-tip in order that the flame may be comparatively thin, and thereby produce the maximum amount of carbon with the minimum amount of light. It will of course be understood that the collecting-wheels and the collecting-cylinder are driven at a very low rate of speed, as indicated by the gearing shown in Fig. 1 of the 100 drawings, in order that the carbon may have sufficient time to collect. As the carbon collects upon the wheels the latter are rotated in frictional engagement with the scrapers 35 and in close proximity to the scrapers 40, whereby the carbon deposited upon the peripheries of the wheels is effectually scraped therefrom, and as the carbon collects and becomes caked upon the heads of the wheels it will eventually engage the scrapers 40, and thereby be 105 removed from the wheels, and all of the carbon scraped from the wheels drops downwardly into the receptacle 2, from which it is fed through the chute 3 by the conveyer 4. It will now be understood that the scrapers 110 40 are disposed out of actual contact with the heads of adjacent wheels, so that there will be a clearance between the same in order that the carbon may fall downwardly between the scrapers and the heads of the wheels and not 115 become banked up between the wheels and the scrapers. Such carbon as escapes from the collecting-wheels is caught by the rotatable cylinder and removed therefrom by the brush or scraper, and such fine carbon as escapes the cylinder is collected upon the screens 53, from which it drops when the 120 weight of the collected carbon is sufficient to overcome the adhesion between the latter and the screens.

The purpose of employing a plurality of comparatively small collecting-wheels separated by vertical interspaces is to overcome 125 the objection to the present long continuous

cylinder, which objection is that such a cylinder soon becomes warped and uneven, and therefore it is impossible to effectually scrape all of the collected carbon from a warped and 5 irregular cylinder. Moreover, I provide each wheel with its own individual scraper, whereby each scraper is wholly independent of the other and may therefore properly conform to the periphery of the wheel with which it co- 10 operates.

Another very important feature of the present invention resides in the independent adjustments of the burner-tips and the flame-confining means, for the reason that while the 15 tips may be set at a predetermined distance from the carbon-collecting wheels in all machines for depositing a certain grade of carbon-black it is necessary to adjust the flame-confining means to the proper draft conditions 20 in each machine, and hence there is a material advantage in having the burners and the flame-confining means independently adjustable over similar devices wherein the relation between the burners and the flame- 25 confining means is fixed and unchangeable, as an adjustment of the burners to overcome defects in the depositing of the carbon-black produces a corresponding adjustment of the flame-confining means, and vice versa, and 30 therefore an adjustment to overcome defects in one of the members would probably produce an injurious effect in the result of the other member.

What I claim is—

35 1. In an apparatus for making carbon-black, the combination with means for producing carbon, of carbon - collecting means made up of a substantially horizontal series of members mounted to rotate in individual 40 substantially parallel vertical planes which are separated by vertical interspaces, each member being arranged with its peripheral edge in coöperative relation with the carbon-producing means and provided with op- 45 posite flat unbroken heads or ends forming collecting-surfaces, and scrapers for the heads of the collecting members.

2. In an apparatus for making carbon-black, the combination with carbon-producing means, of carbon-collecting means made 50 up of a substantially horizontal series of wheels mounted to rotate in individual substantially parallel vertical planes which are separated by vertical interspaces, each member being disposed above the carbon-producing means with its periphery in coöperative relation therewith, and provided with op- 55 site flat unbroken heads or ends which are flush throughout with the respective sides of the periphery of the wheel and forming carbon-collecting surfaces, and scrapers disposed 60 across the heads to scrape carbon therefrom.

3. In an apparatus for making carbon-black, the combination with carbon-producing means, of a plurality of vertically-disposed 65 rotatable carbon-collecting wheels separated by vertical interspaces and having op-

posite flat carbon - collecting heads, and scrapers located between the carbon-collecting wheels, each scraper being in operative 70 relation to the opposite faces of adjacent wheels.

4. In an apparatus for making carbon-black, the combination with a casing, and carbon-producing means housed thereby, of a 75 vertically-disposed rotatable carbon-collecting wheel located above the carbon-producing means and having a flat carbon-collecting head, and a relatively fixed scraper in operative relation to the flat carbon - collecting 80 head of the wheel and having its opposite end supported at opposite sides of the casing.

5. In an apparatus for making carbon-black, the combination with a casing, and carbon-producing means housed therein, of a 85 plurality of vertically-disposed rotatable carbon - collecting wheels having opposite flat carbon-collecting heads and separated by vertical interspaces, scrapers located in the interspaces in frictional engagement with the 90 opposite heads of adjacent wheels, and scraper-supports carried by opposite sides of the casing, the opposite ends of the scrapers being carried by the respective supports.

6. In an apparatus for making carbon-black, the combination with a casing, and carbon-producing means housed therein, of a plurality of vertically-disposed rotatable carbon-collecting wheels mounted upon a common axis and provided with opposite flat carbon-collecting heads, the wheels being separated by vertical interspaces, notched supports carried by the casing and located at opposite sides of the wheels, and scrapers located in the interspaces between the wheels 105 to scrape the heads thereof and having their opposite ends seated in the corresponding notches of the opposite supports.

7. In an apparatus for making carbon-black, the combination with carbon-producing means, of a rotatable shaft located adjacent to the same, a plurality of rotatable carbon-collecting wheels mounted upon the shaft and having their hubs projected at corresponding ends to form spacing devices for the 115 wheels, the latter also having opposite flat carbon-collecting heads, and scrapers located in the spaces between the wheels and in operative relation to the heads thereof.

8. In an apparatus for making carbon-black, the combination with carbon-producing means, of a rotatable shaft located adjacent thereto, a plurality of hollow carbon-collecting wheels mounted thereon, each wheel having one flat integral carbon-collecting head, a hub projected beyond the opposite side of the wheel, and a separate flat carbon-collecting head applied to that side of the wheel having the projected hub portion forming a spacing device for the adjacent 125 wheels, and scrapers situated in the spaces between the wheels and in operative relation to the adjacent heads thereof.

9. An apparatus for making carbon-black,

- having carbon-producing means, in combination with carbon-collecting means made up of a plurality of carbon-collecting wheels mounted to rotate in substantially parallel individual planes which are separated by intermediate spaces, each wheel consisting of a hollow casting, and a flat unbroken head secured to one end of the wheel and forming a carbon-collecting surface. 5
10. In an apparatus for making carbon-black, the combination with carbon-producing means, of a hollow rotatable carbon-collecting wheel in operative relation thereto, and provided upon its inner periphery with integral ribs disposed transversely of the rim thereof, and a flat circular carbon-collecting head secured to corresponding ends of the ribs. 15
11. An apparatus for making carbon-black having carbon-producing means, in combination with carbon-collecting means made up of a plurality of carbon-collecting wheels mounted to rotate in substantially parallel individual planes which are separated by intermediate spaces, each wheel consisting of a hollow cylindrical casting having one integral head, and a separate flat unbroken head secured to the opposite end of the casting, both heads forming carbon-collecting surfaces. 25
12. In an apparatus for making carbon-black, the combination with carbon-producing means, of a rotatable shaft located adjacent thereto, a plurality of carbon-collecting wheels mounted thereon, each wheel comprising an open-ended cylinder having one flat integral carbon-collecting head, a hub projected at the opposite side of the wheel, integral ribs upon the inner periphery of the wheel, and a flat carbon-collecting head closing the open side of the wheel and secured to the adjacent ends of the ribs, fastening means engaging the projected ends of the hubs to connect the wheels to the shaft, said projected hub portions forming spacing devices to separate the wheels, and scrapers located in the spaces between the wheels and in operative relation to the heads thereof. 35
13. In an apparatus for making carbon-black, the combination with a casing and carbon-producing means housed therein, of a rotatable shaft located above the carbon-producing means, a plurality of vertically-disposed carbon-collecting wheels mounted upon the shaft, each wheel having one flat integral carbon-collecting head, a hub projected at the opposite side of the wheel, the projected portion of the hub bearing against the head of the next adjacent wheel and forming a spacing device to separate the two wheels, a separate flat carbon-collecting head applied to the open side of the wheel, fastening means connecting the respective projected hub portions to the shaft, individual scrapers in operative relation to the peripheries of the respective wheels, supports carried by the frame and located at opposite sides of the shaft, and scrapers having their opposite ends carried by the supports and their intermediate portions located in the spaces between the wheels and in operative relation to the heads thereof. 40
14. In an apparatus for making carbon-black, the combination with a collecting-surface, of carbon-producing means embodying a burner, and flame-confining means embracing the burner and adjustable toward and away from the carbon-collecting surface independent of the burners. 45
15. In an apparatus for making carbon-black, the combination with a carbon-collecting surface, of a burner which is adjustable toward and away from said surface, and a flame-confining device embracing the burner and adjustable toward and away from the collecting-surface independently of the adjustment of the burner. 50
16. In an apparatus for making carbon-black, the combination with a collecting-surface, of a burner in co-operative relation thereto, and an open-ended flame-confining device which is adjustable toward and away from the collecting-surface. 55
17. In an apparatus for making carbon-black, the combination with a carbon-collecting surface, of a carbon-producing burner, and an open-ended perforate flame-confining device embracing the burner and adjustable toward and away from the collecting-surface. 60
18. In an apparatus for making carbon-black, the combination with a collecting-surface, of a carbon-producing burner, and a flame-confining device carried by the burner and adjustable thereon toward and away from the carbon-collecting surface. 65
19. In an apparatus for making carbon-black, the combination with a carbon-collecting surface, of a carbon-producing burner having a screw-threaded part, and a flame-confining device embracing the burner and connected to the screw-threaded part thereof for adjustment toward and away from the carbon-collecting surface. 70
20. In an apparatus for making carbon-black, the combination with a carbon-collecting surface, of a carbon-producing burner having a screw-threaded part, a nut adjustably applied to the screw-threaded part, and a flame-confining device supported upon the nut and adjustable therewith toward and away from the collecting-surface. 75
21. In an apparatus for making carbon-black, the combination with a carbon-collecting surface, of a carbon-producing burner having a screw-threaded part, a nut adjustably applied to said screw-threaded part, and a flame-confining device having a cross-bar which is provided with an opening receiving the burner with the cross-bar supported upon and adjustable with the nut. 80
22. In an apparatus for making carbon-black, the combination with a collecting-surface, of a carbon-producing burner having an intermediate tip and opposite terminal tips, the outer tips being externally screw-threaded, nuts applied to the screw-threaded tips, 85

- and a flame-confining device embracing the tips and provided with a pair of cross-bars having openings receiving the terminal tips with the cross-bars supported upon and adjustable with the nuts. 55
23. In an apparatus for making carbon-black, the combination with a carbon-collecting surface, of a carbon-producing burner having an intermediate tip and opposite externally-screw-threaded tips, adjustable nuts upon the screw-threaded tips, and a flame-confining device comprising a skeleton frame having a pair of cross-bars provided with perforations receiving the screw-threaded tips 60 with the cross-bars resting upon and adjustable with the nuts, and a perforate band supported upon and rising from the frame. 65
24. In an apparatus for making carbon-black, the combination with a carbon-collecting surface, of a carbon-producing burner having a screw-threaded nipple, an externally-screw-threaded burner-tip adjustably fitted to the screw-threaded portion of the nipple, a nut adjustably fitted upon the screw-threaded portion of the tip, and a flame-confining device supported upon and adjustable with the nut. 70
25. In an apparatus for making carbon-black, the combination with a cylindrical carbon-collecting device mounted to rotate upon a horizontal axis, of a carbon-producing burner having a plurality of burner-tips disposed in the vertical plane of the cylinder, with their upper ends arranged in an arc eccentric to that of the collecting-cylinder. 75
26. In an apparatus for making carbon-black, the combination with a vertically-disposed rotatable carbon-collecting wheel, of a carbon-producing burner having a plurality 80 of tips alined transversely of the burner in the vertical plane of the wheel, the outer tips being nearer to the surface of the wheel than the inner tips. 85
27. In an apparatus for making carbon-black, the combination with a casing, of a gas-service pipe therein, a plurality of burners carried thereby and disposed transversely thereof, each burner having a plurality of screw-threaded nipples, externally-screw-threaded 90 burner-tips adjustably fitted to the nipples, adjustable nuts fitted upon the outermost screw-threaded tips, an open frame embracing the tips and having cross-bars provided 95
- with openings loosely receiving the outermost tips with the cross-bars supported upon and adjustable with the nuts, an upstanding foraminous band carried by the frame, a horizontal rotatable shaft alined longitudinally above the gas-service pipe, a plurality of rotatable carbon-collecting wheels mounted upon the shaft and separated by vertical interspaces, each wheel having opposite flat carbon-collecting heads, supports carried within the casing and at opposite sides of the shaft, scrapers lying between the respective 60 wheels in frictional engagement with the adjacent heads thereof to scrape the carbon therefrom and having their opposite ends carried by the respective supports, and individual weighted scrapers in frictional engagement with the peripheries of the respective 65 wheels. 70
28. In an apparatus for making carbon-black, the combination with carbon-producing means, of rotatable carbon-collecting wheels having opposite flat carbon-collecting heads and flat peripheries, individual scrapers engaging the periphery of each wheel, and scrapers arranged between each pair of wheels to scrape the heads. 80
29. In an apparatus for making carbon-black, the combination with carbon-producing means, of a rotatable shaft located adjacent thereto, a plurality of hollow carbon-collecting wheels mounted thereon, each wheel having one flat integral head, a hub projected beyond the opposite side of the wheel, and a separate flat head applied to that side of the wheel having the projected hub portion forming a spacing device for the adjacent wheels. 85
30. In combination with the carbon-collecting means, the carbon-producing means arranged below and spaced from the carbon-collecting means, of flame-confining means arranged in the space between the carbon-collecting means and the carbon-producing means and adjustable independently of the carbon-producing means for the purpose described. 90

In testimony that I claim the foregoing as my own I have hereto affixed my signature in the presence of two witnesses.

JOHN LEWIS MANN.
